INDICATING DEVICE

Leonard B. Emerson, Framingham, and Richard P. Curtis,
Marblehead, Mass., assignors to Raytheon Company,
Waltham, Mass., a corporation of Delaware

Filed Nov. 27, 1959, Ser. No. 58,487

Term of patent 14 years

(Cl. D26—1)

FIG. 1

FIG. 2

Fig. 1 is a perspective view of an indicating device, showing our new design; and

Fig. 2 is a side elevational view thereof.

The broken line showing of legible matter in Fig. 1 is for illustrative purposes only.

The dominant features of our new design are shown in solid lines in the drawing.

We claim:

The ornamental design for an indicating device, substantially as shown and described.
